CALENDAR DIAL

Louis M. Hall, Memphis, Tenn.

Application September 17, 1932, Serial No. 633,658

2 Claims. (Cl. 185—39)

This invention relates to games and more particularly to a calendar dial game which involves an element of skill and a degree of chance.

An object of this invention is to provide a game structure wherein a spinning or rotating member is provided which is adapted to be operated by a person in such a manner so that it will stop at a predetermined point.

Another object of this invention is to provide a device of this kind which is so constructed that the working parts thereof are sealed within the housing so that they cannot be disturbed or interfered with, thereby preventing any unfair advantage being taken in the playing of the game.

A further object of this invention is to provide a device of this kind which is particularly designed for use by merchants in the sale of merchandise, the device being operated by a customer with the understanding that in the event the rotating or spinning member stop at a predetermined point, the customer will receive a prize or the like.

The above and various other objects and advantages of this invention will in part be described and in part be understood from the following detailed description of the present preferred embodiment, the same being illustrated in the accompanying drawing, wherein:

Figure 1 is a detail front elevation of a device constructed according to the preferred embodiment of this invention.

Figure 2 is an enlarged fragmentary front elevation of the working parts of the device enclosed within the housing.

Figure 3 is a fragmentary sectional view taken on the line 3—3 of Figure 1.

Figure 4 is a fragmentary perspective view of the ratchet holding member.

Figure 5 is a perspective view of the pawl removed from the ratchet holding member and showing in dotted line the manner in which the plunger or operator engages the pawl for operation.

Referring to the drawing wherein like numerals of reference designate corresponding parts throughout the several views, the numeral 10 designates generally a base which has a housing 11 mounted thereon. This housing is open on the front and is provided with a glass window or the like, and a rear wall 12 is provided with a peripheral flange 13 which telescopes partly into the body 14 of the housing and is secured thereto by means of bolts, rivets, or the like.

Axially of the annular housing 14 is a fixed

shaft or post 15 which has secured thereto a pointer or arm 16 in the present instance mounted in vertical position. A disk or plate 17 is secured to the forward end of a hub or bushing 18 rotatably mounted on the shaft or stud 15, and a dial 19 is secured to the front face of this disk 17 and this dial carries indicia 20 indicative of the days of the month.

These indicia are preferably formed of alternate colors such as red and black, and the numbers in the present instance run from 1 to 31 inclusive. A toothed wheel or ratchet 21 is secured to the hub or bushing 18 at the rear end thereof, and this wheel rotates against a washer 22, which is fixedly secured to the shaft 15 at a point disposed inwardly from the rear end thereof.

A pivoted arm 23, which is mounted on a pivot 24, extends in the direction of the post 15, and is provided with a reduced and upwardly offset arm or pawl holding member 25 at the inner end thereof which terminates in a head or plate 26. A substantially U-shaped pawl 27 engages about this arm or extension 25, and is held in engagement therewith by means of a relatively strong spring 28 which is secured at one end to one leg of the pawl member 27, and the other end of the spring 28 is secured to the back plate 12.

The ratchet engaging portion of the pawl member 27 is so constructed that it will be normally disposed out of engagement with the ratchet 21 so that this ratchet, together with the disk 17 and the dial 19, may rotate freely on the shaft 15. A stop member 29 is carried by the back plate 12 for engagement with the inner end of the rock 35 arm or lever 23.

An operating member or plunger, generally designated as 30, is mounted for sliding movement on the inner surface of the back plate 12, and this plunger has an extension 31 disposed outwardly 40 of the housing 14 so that the plunger can be operated with the housing in sealed condition.

The inner end of the plunger 30 is provided with a head or enlarged portion 32 having a slot 33 therein engaged about the post 15 and the upper end of this slot 33 terminates in an inclined portion 34, the purpose for which will be hereinafter described. The side of the head portion 32 adjacent the rock arm 23 is provided with an offset pawl engaging member 35 which engages 50 a leg 36 carried by the pawl 27. A spring 37 has one end thereof secured to the plunger 30 and the other end secured to the back plate 12 so that the plunger will be automatically returned to inoperative position upon release of pressure from 55

the extension 31. The head portion 32 is disposed between a pair of washers 38 carried by the post or shaft 15 so that the plunger 30 can readily slide downwardly and carry therewith 5 the rock arm 23.

In the use and operation of this device, the housing 11 will be normally sealed and the device may be mounted on a counter or the like with the plunger operating member 31 extending 10 upwardly through the housing for operation. Upon depression of the plunger 30, the dog or offset portion 35 of the sliding head member 32 will contact with the lug 36 carried by the pawl 27 and will swing the arm 32 past the axis of the 15 shaft 15. Due to the substantially V-shaped construction of the pawl member 27, as this member is engaged by the plunger 30, it will be rocked slightly in a direction toward the toothed wheel 21 so that it will contact with the teeth of this 20 wheel, and when the plunger 30 moves downwardly to a position where the inclined portion 34 contacts with the post 15, the plunger 30 will be shifted in a relatively rapid degree out of the path of the arm 23.

25 The spring 28 will then automatically return the arm to its uppermost position and upon return of this arm, the innermost end of the pawl 27 will strike the teeth of the wheel 21 and cause this wheel to assume a relatively rapid spinning 30 motion and carry therewith the disk 17 and the dial 19. In this manner, the plunger 30 cannot be stopped in its downward movement at any desired point so as to effect a particular degree 35 of tension on the spring 28 although, of course, it can be struck with a relatively strong force and forced downwardly rapidly so as to effect a very rapid spinning of the dial 19.

30 The device herein disclosed is not designed for use in connection with any coin controlled mechanism although it may, of course, be operatively associated with such a mechanism, if desired.

In the present instance, the device is designed

for use by merchants in order to increase the interest of the trade by giving, as a prize, an additional article similar to the one already purchased if the customer turns the dial so that the dial will stop with the pointer over a number which is the same as the day of the month on which the article is purchased. 5

It is, of course, understood that various changes and modifications may be made in the details of construction and design of the above 10 specifically described embodiment of this invention without departing from the spirit thereof, such changes and modifications being restricted only by the scope of the following claims. 15

What is claimed is:—

1. A device as described, comprising a rotatable member, means for mounting said member for free rotation, a toothed wheel rotatable with said member, a swingable arm, a spring pressed pawl carried by said arm and adapted to engage 20 said wheel for rotation thereof, and operating means for swinging said pawl into operative position, said operating means comprising an elongated member having a slot therein with parallel sides and terminating at one end in a cam 25 portion to shift said elongated member laterally into released position.

2. A device as described, comprising a rotatable member, means for mounting said member for free rotation, a toothed wheel rotatable with said 30 member, a movable arm, a pawl on the arm, a spring for holding the arm and pawl in released position and operating means for moving the arm into wheel rotating position, said operating means including an elongated member having a slot 35 therein loosely receiving said mounting means for said rotatable member, a lug carried by said elongated member positioned in the path of said pawl, and a cam at one end of said slot for swinging said elongated member laterally into released 40 position.

LOUIS M. HALL.
